UNITED STATES PATENT OFFICE

PACOLO ORLANDO, OF FIUME, ITALY, ASSIGNOR TO SILURIFICIO WHITEHEAD DI FIUME SOCIETA ANONIMA, OF FIUME, ITALY, A COMPANY OF ITALY

TORPEDO

Application filed August 20, 1930, Serial No. 476,652, and in Italy August 30, 1929.

This invention has for its object a device for automotive torpedoes by means of which when an automotive torpedo at any time of its run tends to sink, its weight is automatically reduced through the discharge of compressed air stored in a motor-feeding vessel, the weight of said air having, as known, great importance as to torpedo buoyancy.

This invention comprises also means for causing said air discharge in conditions to set the torpedo upright and to assist its buoyancy.

On the annexed drawings:

Figure 1 is a fragmentary section, with parts omitted, of an automotive torpedo equipped according to this invention;

Figure 2 is a fragmentary transverse section of the same on line 2—2 of Figure 1;

Figure 3 is a fragmentary section on an enlarged scale of the device of this invention for discharging compressed air from the compressed air vessel feeding the torpedo motor;

Figure 4 is a separate and fragmentary plan view of a detail on line 4—4 of Figure 3, with the torpedo shell removed;

Figure 5 is a fragmentary section on line 5—5 of Fig. 3.

As shown on the drawings, within the torpedo shell 1 is fastened a rim 5 which connects the torpedo head shell 1 with the air vessel 3 and provides a peripheral set of nozzles 6 connected with a space 7 left intermediate the bow wall 8 of vessel 3 and a partition 9 fastened on rim 5 and on a valve casing 10 located in space 2 within head 1.

In a cylinder 11 threaded in a central bore of front partition 8 of compressed air vessel 3 (Figures 1 and 3) is mounted to reciprocate a valve 12 having a balancing port 13 and a pilot valve 14 acted on by a spring 57, the stem of said pilot valve 14 having an outer head 15; the differential valve 12—14 thus provided controls air flow through ports 16 and 17 of cylinders 11 and between the inside of vessel 3 and space 7.

In a sleeve 18 of casing 10 fastened on partition 9 a piston 19 is mounted to reciprocate, said piston having an adjusting screw 20 adapted to abut on head 15 and a throughout

port 21; a link 23 is fulcrumed at 22 on piston 19 and is pivoted at 24 with a similar link 25 fulcrumed at 26 on a piston 27 hereinafter described thus providing a toggle gear, the interconnected ends of links 23, 25 extending beyond bushing 18 through slot 61 of the same, while a port 56 connects the inside of sleeve 18 with the inside of casing 10; a piston 27 is mounted to move against pressure of a spring 28 in a seat 29 which is loose in sleeve 18 and is resiliently held in position therein by a spring 30 and a plug 31 fastened in the mouth of sleeve 18.

A tube 32 leads from casing 10 to bow ballast water compartment 4 of torpedo (Figures 1 and 3). Casing 10 is encircled by a movable frame 33 (Figures 3 and 5) whose bottom portion is connected by means of rod 34 and stud 35 with a shoe 36 fulcrumed at 37 on a seat 37 of torpedo shell 1.

The frame 33 has a tappet 38 operative on a plunger 39 mounted to reciprocate through casing 10 and bearing on the ends of toggle-links 23—25 interconnected by pivot pin 24, the top end of said frame 33 is connected by a rod 40 with a hydrostatic diaphragm 41 which is actuated by outstanding water pressure against the action of a spring 42 which is seated in a seat 60 fastened by collar 52 on the torpedo shell 1.

In lugs 43 solid with top plate 44 of diaphragm 41 a fork 45 is pivoted at 58, said fork being acted on by springs 59 engaged with said fork 45 and plate 44 at 46 and 47 respectively; said fork has an arm 48 whose head 49 may project outwardly through an opening 50 of a cover 51 closing the collar 52 and seat 60 where diaphragm 41 is located; teeth 53 are provided on the pivot fork ends they being adapted to engage lower surface of cover 51.

The communication intermediate casing 10 and space 7 is made through ports 62 and is normally cut off by a tapering annular valve 54 which is mounted to reciprocate on sleeve 18 and is forced by spring 55 on its seat provided in casing 10.

When the torpedo is in the launching tube therefor (not shown) shoe 36 abuts on the internal surface of said tube and said shoe

36 with frame 33 and parts connected therewith are prevented from moving, they being thus held in position shown in Figure 3.

When the torpedo has been launched and 5 in its run it tends to sink and reaches a depth for which diaphragm 41 and spring 42 have been set to operate, said diaphragm 41 moves inwardly against the action of spring 42, and then it is engaged in the position it takes up 10 because teeth 53 of fork 45 under action of springs 59 abut on lower face of cover 51; then arm 48 is caused to carry the manipulating head 49 to outside of the torpedo shell for its subsequent manipulation.

15 The displacement of diaphragm 41 and of rod 40 connected with it causes frame 33 to move down it then freely moving in this direction, because shoe 36 connected therewith by rod 34 is free to swing outwardly 20 around its pivot 37, said shoe being no longer engaged by the surface of the launching tube.

Frame 33 on moving down shifts plunger 39 downward, the toggle gear 23, 25 being thus actuated at pivot point 24.

25 Piston 27 is first caused to move back against the action of spring 28 and then the spreading motion of toggle gear 23, 25 after spring 28 is compressed causes a backward motion of piston 19 whose stem 20 acts on 30 head 15 and thus opens pilot valve 14 and then the main valve 12.

Then air compressed under high pressure within vessel 3 flows through 16, 13, 17, 21 into sleeve 18 and a portion of said air may flow 35 through tube 32 into compartment 4 to expel water contained therein, by a device forming the subject matter of my co-pending application filed at the same date hereof under Serial Number 476,651.

40 The remaining portion of compressed air flows into sleeve 18 and issues therefrom through port 56, and then said air opens valve 54, flows through ports 62 and enters space 7 from which it issues through nozzles 6 dis- 45 charging it towards torpedo stern.

Air jets issuing from nozzles 6 and directed sternward owing to the water reaction produce on said nozzles and therefore on the torpedo an upward action; then the torpedo sits 50 upright and the reduction of weight depending upon the air discharge is assisted by a positive upward action causing the torpedo to float.

55 Diaphragm 41 and stem 40 with parts actuated by said stem are held in the position they took up when the described operation is completed by teeth 53 abutting on cover 51.

60 When the torpedo has been recovered an operator acts on head 49 of fork 45 to release the gear and enable valves 14 and 12 to close under the action of spring 57, the torpedo being thus in conditions for a subsequent loading and run.

65 The described arrangement provides for

securing automatically the discharge of air from vessel 3 and for obtaining an action which assists the torpedo buoyancy when the torpedo reaches a predetermined depth after being launched, while shoe 36 serves to prevent the operation of the device and the discharge of the air when the torpedo is within a launching tube of a submarine boat and this boat sinks at a larger depth than that for which the air release control means (as diaphragm 41) has been set.

What I claim as my invention and desire to secure by United States Letters Patent is:—

1. A device for reducing the weight of an automotive torpedo driven by an air motor fed by a compressed air vessel when it tends to sink beyond a predetermined depth, comprising a set of air discharging nozzles opening sternward through the torpedo shell, means providing a passage for air from said vessel to said nozzles, an exhaust valve located in said passage, and adjustable means subject to the pressure of the outstanding water and actuating said valve to open said passage when the torpedo reaches said predetermined depth.

2. A device for reducing the weight of an automotive torpedo driven by an air motor fed by a compressed air vessel when it tends to sink beyond a predetermined depth, comprising a set of air discharging nozzles opening sternward through the torpedo shell, means providing a passage for air from said vessel to said nozzles, an exhaust valve located in said passage, adjustable means subject to the pressure of the outstanding water and actuating said valve to open said passage when the torpedo reaches said predetermined depth, and means adapted to engage the torpedo launching means and to restrict the actuation of said valve when so engaged.

3. A device for reducing the weight of an automotive torpedo driven by an air motor fed by a compressed air vessel when it tends to sink beyond a predetermined depth, comprising a set of air discharging nozzles opening sternward through the torpedo shell, means providing a passage for air from said vessel to said nozzles, an exhaust valve located in said passage and comprising a valve member, a toggle gear operative on said exhaust valve member, a member subject to the pressure of the outstanding water and actuating said toggle gear, means for adjusting the pressure under which said pressure responsive member is made operative, and means adapted to engage the torpedo launching means and to restrict the operation of said pressure responsive member and valve when so engaged.

4. A device for reducing the weight of an automotive torpedo driven by an air motor fed by a compressed air vessel when it tends to sink beyond a predetermined depth, comprising a set of air discharging nozzles open-

ing sternward through the torpedo shell, means providing a passage for air from said vessel to said nozzles, a differential exhaust valve located in said passage and comprising valve members adapted to operate in sequence, a toggle gear operative on said differential valve members, a member subject to the pressure of the outstanding water and actuating said toggle gear, means for adjusting the pressure under which said pressure responsive member is made operative, and means adapted to engage the torpedo launching means and to restrict the operation of said pressure responsive member and valve when so engaged.

5. A device for reducing the weight of an automotive torpedo driven by an air motor fed by a compressed air vessel when it tends to sink beyond a predetermined depth, comprising a set of air discharging nozzles opening sternward through the torpedo shell, means providing a passage for air from said vessel to said nozzles, an exhaust valve located in said passage, a flow restricting valve in said passage and means for resiliently holding said flow valve closed, means subject to the pressure of the outstanding water and actuating said exhaust valve, means for adjusting the pressure under which said exhaust valve actuating means is made operative, and means adapted to engage the torpedo launching means and to restrict the operation of said exhaust valve when so engaged.

6. A device for reducing the weight of an automotive torpedo driven by an air motor fed by a compressed air vessel when it tends to sink beyond a predetermined depth, comprising an exhaust valve controlling an outlet for said vessel, adjustable means responsive to the pressure of the outstanding water and actuating said valve to open said outlet when the torpedo reaches said predetermined depth, and locking means made operative by the operation of said water pressure responsive means to hold said valve in open position.

7. A device for reducing the weight of an automotive torpedo driven by an air motor fed by a compressed air vessel when it tends to sink beyond a predetermined depth, comprising an exhaust valve controlling an outlet for said vessel, adjustable means responsive to the pressure of the outstanding water and actuating said valve to open said outlet when the torpedo reaches said predetermined depth, locking means made operative by the operation of said water pressure responsive means to hold said valve in open position, and manipulating means operable from outside of the torpedo shell to release said locking means.

8. A device for reducing the weight of an automotive torpedo driven by an air motor fed by a compressed air vessel when it tends to sink beyond a predetermined depth, com-

prising a set of air discharging nozzles opening sternward through the torpedo shell, means providing a passage for air from said vessel to said nozzles, an exhaust valve located in said passage and comprising a valve member, a flow restricting valve in said passage and means for resiliently holding said flow valve closed, a toggle gear operative on said valve member, a diaphragm subject to the pressure of the outstanding water and actuating said toggle gear, means for adjusting the pressure under which said diaphragm is made operative, locking means made operative by displacement of said water pressure operated diaphragm to hold said exhaust valve in open position, manipulating means operable from outside of the torpedo shell to release said locking means and means adapted to engage the torpedo launching means and to restrict the operation of said diaphragm and exhaust valve when so engaged.

9. A device for reducing the weight of an automotive torpedo driven by an air motor fed by a compressed air vessel when it tends to sink beyond a predetermined depth, comprising a set of air discharging nozzles opening sternward through the torpedo shell, means providing a passage for air from said vessel to said nozzles, an exhaust differential valve located in said passage and comprising valve members adapted to operate in sequence, a flow restricting valve in said passage and means for resiliently holding said flow valve closed, a toggle gear operative on said differential valve members, a diaphragm subject to the pressure of the outstanding water and actuating said toggle gear, means for adjusting the pressure under which said diaphragm is made operative, locking means made operative by displacement of said water pressure operated diaphragm to hold said exhaust valve in open position, manipulating means operable from outside of the torpedo shell to release said locking means, and means adapted to engage the torpedo launching means and to restrict the operation of said diaphragm and exhaust valve when so engaged.

10. A device for reducing the weight of an automotive torpedo driven by an air motor fed by a compressed air vessel when it tends to sink beyond a predetermined depth, comprising a set of air discharging nozzles opening sternward through the torpedo shell, means providing a passage for air from said vessel to said nozzles, an exhaust differential valve located in said passage and comprising a number of valve members adapted to operate in sequence, a flow restricting valve in said passage and means for resiliently holding said flow valve closed, a toggle gear operative on said differential valve members, a diaphragm subject to the pressure of the outstanding water and actuating said toggle gear, means for adjusting the pressure under

which said diaphragm is made operative, locking means made operative by displacement of said water pressure operated diaphragm to hold said exhaust valve in open position, manipulating means operable from outside of the torpedo shell to release said locking means, means adapted to engage the torpedo launching means and to restrict the operation of said diaphragm and exhaust valve when so engaged, a ballast water compartment in said torpedo, and means conveying a portion of air discharged from said exhaust valve to said ballast water compartment to expel water therefrom.

15 In testimony whereof, I affix my signature.
PAOLO ORLANDO.
